UNITED STATES PATENT OFFICE.

JOHN M. SWEENEY, OF LEBANON, ASSIGNOR OF ONE-HALF TO JULIUS LANG, JR., OF CINCINNATI, OHIO.

SHOW-CASE.

SPECIFICATION forming part of Letters Patent No. 445,129, dated January 20, 1891.

Application filed September 29, 1890. Serial No. 366,477. (No model.)

To all whom it may concern:

Be it known that I, JOHN M. SWEENEY, a citizen of the United States, and a resident of Lebanon, in the county of Warren and State 5 of Ohio, have invented certain new and useful Improvements in Show-Cases, of which the following is a specification.

The object of my invention is to provide a show-case with automatically-opening doors 10 or shutters.

The various features of my invention will be fully set forth in the description of the accompanying drawings, making a part of this specification, in which—

15 Figure 1 is an elevation, partly broken away, of the rear side of the case, showing the door open. Fig. 2 is a central vertical section of the spring-housing. Fig. 3 is a top plan view of one corner of the show-case.

20 1 represents the show-case proper; 2, a metallic housing which is secured to the show-case by lugs 3 and screws or rivets 4.

5 represents ordinary shutters, doors, or sash-frames forming the top of the show-case.

25 6 represents an axial rod journaled in the bearings 7, formed in the housing. On each end of said axial rod are curved crank-arms 8, which project inside of the box under the sash-doors, as shown in Figs. 1 and 3.

30 9 represents a spring, one end of which is secured to the axial shaft 7 and the other end is secured to the washer 10. Said washer is provided with holes 11, so that it may be turned on the rod to coil and uncoil the spring,

35 which is locked in position by dropping a pin in one of said holes after it has been turned to the proper position. In Fig. 1, 12 represents such pins on each of the washers 10. Either side of rod 6 is provided with the du-

40 plicate spring washers and arms. The arms 8 engage in and move in inclined curved cam-guides A. Said guides are inclined upward and are attached to the under side of the sash 5, as shown in Fig. 1, their outer ends resting

45 in slots in brackets a, also secured to the sash. The mode of operation of my device is as

follows: The spring 9 is adjusted by turning the washer 10 so that the recoil of the spring will readily raise the sash-door 5, and they are thrown by the force of said spring into the 50 position shown in Fig. 1. When it is desired to close the doors, they are forced down and held by the catch B, which engages with the doors and holds them in position. When the catch is released, the recoil of the spring, acting 55 through the arms 8 in the cam-guides A, will instantly open the doors of the show-case upward in position shown in Fig. 1.

Having described my invention, what I claim is—

1. In combination with the show-case, the axial rod carrying crank-arms engaging in guides attached to the sash-doors, so that the recoil of the spring will force the arm through the guides and elevate the doors, substantially as described.

2. In combination with a show-case, the axial rod 6, inclosed in a housing 2 and provided with one or more springs and crank-arms engaging with cam-slots in compartment-doors, whereby the same are automatically opened when the spring is released, substantially as described.

3. In combination with a show-case having one or more doors, axial rod carrying lifting-arms journaled in cam-guides attached to the compartment-doors, and a catch B for holding said door closed against the action of the opening lifting force, substantially as described.

4. In a show-case, the combination of arms 8 with the cam-guides A, attached to the doors, and a spring device for actuating said arms to open the doors, substantially as described.

In testimony whereof I have hereunto set my hand.

JOHN M. SWEENEY.
